UNITED STATES PATENT OFFICE.

BERTIE S. HARRINGTON, OF FORT WORTH, TEXAS.

AUTOMATIC DOOR-OPERATING MECHANISM.

Application filed July 6, 1926. Serial No. 120,604.

The principal object of this invention is to provide an improved mechanism which, when actuated, will automatically open a door, hold it open for a predetermined 5 length of time, and close it at the expiration of such time.

Other objects and advantages of the invention will be apparent to those skilled in the art upon an understanding of the construction, arrangement and operation of a mechanism embodying the invention. Such a mechanism is presented herein for the purpose of exemplification, but it will of course be understood that the invention is also susceptible of embodiment in various other modified forms coming equally within the comprehensive scope of the appended claims.

In the preceding drawings:

Fig. 1 is a perspective view of a door 20 which is equipped with a mechanism constructed in accordance with the invention;

Fig. 2 is a side elevation of the mechanism;

Fig. 3 is a vertical section through the mechanism; and

Fig. 4 is a similar section through a portion of the mechanism.

It will be observed in the drawings that the door 10 to which the mechanism of the invention is applied is hinged in the usual 30 way along one vertical edge, and has attached to the opposite sides thereof two cords 11 and 12. The cord 11 is connected with a weight 13, and is trained over two pulleys 14 and 15 in such a way as to tend to pull the 35 door closed by the gravitational force exerted thereon by the weight 13. The cord 12 is connected with a heavier weight 16 which is slidably mounted in an upright casing 17, and is trained over a pulley 18 in such a way as 40 to overbalance the action of the weight 13 and pull the door open by the gravitational force exerted thereon by the weight 16. It will thus be seen that the two weights 13 and 16 pull against the door in opposition to 45 each other, the weight 16 being enough heavier than the weight 13 to overcome the effect of the latter and open the door, and the weight 13 being sufficiently heavy to close the door when the weight 16 is held 50 against downward movement in the top of the tube 17. A hook 19 is pivotally mounted on the casing 17 for the purpose of holding the weight 16, and extends through an aperture in the casing into a position underlying 55 the lower edge of the weight 16.

A person wishing the door to open simply

pulls upon either one of two cords 20 and 21, depending upon which side of the door he happens to be on. The cords 20 and 21 are branches of a single operating cord 22 which is trained over a pulley 23 and connects with a lever arm 24 on the hook 19, and the resulting movement of the cord 22 swings the hook 19 outwardly and withdraws the same from engagement with the bottom 60 of the weight 16, whereupon the latter is permitted to move downwardly in the casing 17 and open the door gently under the modifying influence of the counterweight 13.

The weight 16 is provided with a longitudinally extending bore 25, and slides up and down over a stationary piston 26 which is mounted on the upper end of a hollow stem 27 connected with a source of air or other fluid under pressure. As the weight 16 approaches the lower end of its travel, a plunger 28 secured to the bottom of the weight enters an oil filled dash pot 29 in the bottom of the casing 17, and the downward movement of the weight is retarded and not 70 completed until the oil 30 pocketed in the dash pot has been expressed therefrom through one or both of two small outlets 31 and 32 which are adjustable as to size by means of suitable needle valves 33.

If it is desired that the door remain open a comparatively short period, for instance, five seconds, the oil 30 in the dash pot 29 is permitted to leave the latter through both of the outlets 31 and 32. If it is desired that 75 the door remain open a longer period, for instance fifteen seconds, a longer pull is given, either initially or later on, to the cord 22, causing the lever arm 24 to engage with and lift a lug 34 on the upper end 80 of a rod 35 which extends downwardly through an aperture in the end of the arm 24. The lower end of the rod 35 connects with a lever 36, and the lever 36, when thus moved, engages with and shifts the stem of a valve 37 upwardly, thereby cutting off communication between the dash pot 29 and the outlet 32, and causing all of the oil pocketed 85 in the dash pot to pass through the other outlet 31.

When the weight 16 finally reaches the lower end of its travel, the valve 37 which shuts off the outlet 32 is shifted into an inoperative position again by the engagement of a shoulder 38 on the plunger 28 with the stem of the valve 37. At the same time, a small lever 39 on the top of the piston 26

is depressed by engagement with the underside 40 of the top of the weight 16, and shifts the stem of a valve 41 in the piston downwardly. The downward movement of the 6 valve 41 connects the passageway 42 in the pipe 27 containing the compressed air with a port 43 which communicates with the chamber 44 between the top of the piston and the undersurface 40 of the top of the weight 10 16, and compressed air is accordingly permitted to flow into the chamber 44, instantly raising the weight 16 to its uppermost position in the casing 17 and thereby permitting the weight 13 to close the door. As soon as 15 the weight 16 reaches the upper end of its travel, the hook 19 swings by gravity into its former position below and in supporting engagement with the bottom of the weight, and the upper surface 45 of the bottom of 20 the weight engages with and lifts the stem of the valve 41 in the piston 26, shutting off communication between the compressed air passageway 42 and the port 43, and opening communication between the latter and a port 25 46 which communicates with a vented chamber 46 in the weight below the piston 26.

The operation of the mechanism may be summarized as follows:

In the normal closed position of the door, 30 the weight 13 is down, and the weight 16 is up and latched in such position by the hook 19. When a person wishes the door to open for a short period of time, such as for the purpose of permitting a single vehicle 35 to pass therethrough, he pulls the cord 20 (or 21) as he approaches the door with the truck. The movement of the cord 20 (or 21) is transmitted to the cord 22, and the hook 19 is withdrawn from beneath the 40 weight 16, permitting the weight to move downwardly and open the door. As the weight 16 approaches the lower end of its travel, it is retarded and does not bottom until five seconds have elapsed, or any other 45 period of time for which the valves 33 in the ports 31 and 32 have been set. As soon as the weight does bottom, however, the valve 41 in the stationary piston 26 is shifted downwardly by engagement of the under- 50 surface 40 of the weight 16 with the lever 39, and compressed air flows into the chamber 44 in the weight above the piston 26, thereby immediately elevating the weight 16 to its uppermost position, and permitting the weight 13 to close the door. When the 55 weight reaches such position, the hook 19 reengages with and supports the same, and the valve 41 is shifted downwardly by engagement of the stem thereof with the upper 60 surface 45 of the bottom of the weight, thereby establishing communication between the upper closed chamber 44 in the weight and the lower vented chamber 46. When a person wishes the door to open for a comparatively long period of time, such as to

70 permit the passage therethrough of a train of trucks, he gives a longer pull on the cord 20 (or 21), and the operation of the mechanism is substantially the same as above described, the only difference being that the lug 34 on the rod 35 is shifted upwardly by the lever arm 24 and acts through the rod 35 and the lever 36 to raise the valve 37 and cut off the outlet 32 leading from the dash pot 29, thus forcing all of the oil 75 30 in the dash pot to flow out of the same through the other outlet 31 and requiring a proportionately longer period of time for such flow to be completed.

75 The mechanism of the invention is illustrated, described and claimed herein as used for opening and closing a door, but it will be appreciated that it might be used with equally good results for many other different purposes. The term "door," therefore, as used in the claims, is intended to designate generally any kind of member capable of being moved in opposite directions.

80 I claim:

85 1. A door-operating mechanism, including means for opening a door, means under manual control for actuating the opening means, and means operating automatically a predetermined length of time after the door has opened for closing the same and placing the opening means in condition for operation again when actuated.

90 2. A door-operating mechanism, including means for opening a door, means for closing the door, and means operating automatically a predetermined length of time after the opening means has functioned for re-setting the opening means and causing the closing means to function.

95 3. A door-operating mechanism, including means for opening a door, means under manual control for actuating the opening means, means for closing the door automatically after the same has stood open a certain length of time, and means also actuated by the means actuating the opening means for varying such time.

100 4. A door-operating mechanism, including two weights, one of which is mounted in such a way as to tend to move a door in one direction, and the other of which is lighter and is mounted in such a way as to tend to move the door in the other direction, and means operable automatically a predetermined time after operation of the heavier weight for rendering the same inoperative whereby to permit operation of the lighter weight.

105 5. A door-operating mechanism, including two weights, one of which is mounted in such a way as to tend to open a door, and the other of which is lighter and is mounted in such a way as to tend to close the door, and means for automatically raising the heavier

weight a predetermined length of time after the lowering of the same and opening of the door whereby to permit lowering of the lighter weight and closing of the door.

5 6. A door-operating mechanism, including two weights, one of which is mounted in such a way as to tend to open a door, and the other of which is lighter and is mounted in such a way as to tend to close the door,

10 a latch for supporting the heavier weight in its raised position, means releasing the latch to permit the heavier weight to open

the door, a stationary piston disposed within a chamber in the heavier weight, and means operating automatically after the 15 heavier weight reaches its lowered position for conducting a fluid under pressure into the chamber above the piston, whereby to return the heavier weight to its raised and latched position and permit the lighter 20 weight to close the door.

In testimony whereof I have hereunto subscribed by name.

BERTIE S. HARRINGTON.
